US0D1027415S

(12) **United States Design Patent** (10) **Patent No.:** **US D1,027,415 S**
(45) **Date of Patent:** **** May 21, 2024**

(54) **MID-SOLE CLEAT**

(71) Applicant: **Geroline Inc.**, Fonthill (CA)

(72) Inventors: **John Savio**, Fonthill (CA); **Greg McCandless**, Fonthill (CA)

(73) Assignee: **Geroline Inc.**, St. Catharines (CA)

(**) Term: **15 Years**

(21) Appl. No.: **29/869,298**

(22) Filed: **Dec. 28, 2022**

Related U.S. Application Data

(62) Division of application No. 29/724,249, filed on Feb. 13, 2020, now Pat. No. Des. 1,000,081.

(57) **CLAIM**

The ornamental design for a mid-sole cleat, as shown and described.

DESCRIPTION

FIG. 1 is a perspective view of the mid-sole cleat;

FIG. 2 is a side view thereof;

FIG. 3 is a top view thereof;

FIG. 4 is a side view thereof;

FIG. 5 is a bottom view thereof;

FIG. 6 is a front view thereof; and,

FIG. 7 is a back view thereof.

The dashed lines show various portions and other elements in the figures for the purpose of illustrating portions of the mid-sole cleat that form no part of the claimed design.

1 Claim, 3 Drawing Sheets
